UNITED STATES PATENT OFFICE.

THOMAS W. MORGAN, OF WATERLOO, IOWA, ASSIGNOR TO WILBUR W. MARSH, OF WATERLOO, IOWA.

MAGNETO-GENERATOR.

1,119,165.

Specification of Letters Patent.

Patented Dec. 1, 1914.

Application filed March 25, 1912. Serial No. 686,205.

To all whom it may concern:

Be it known that I, THOMAS W. MORGAN, a citizen of the United States, and a resident of Waterloo, in the county of Blackhawk and State of Iowa, have invented certain new and useful Improvements in Magneto-Generators, of which the following is a full, clear, and exact specification.

My invention relates to magneto generators, and has more particular reference to improvements in magnetos of the class used in ignition systems for internal combustion engines.

One of the objects of my invention is to provide an improved magneto which will be simple, durable and reliable in construction, and effective and efficient in operation.

Another object of my invention is to provide an improved magneto structure which will be so constructed and arranged that the parts thereof will be interchangeable and may be manufactured in large quantities and assembled without adjustment.

A further object of my invention is to provide an improved field pole-piece which may be formed up from sheet metal without the aid of expensive machine work.

Another object of my invention is to provide a magneto having improved means for conveniently timing the magneto with the engine with which it is used, without disturbing the parts of the magneto or necessitating its being disassembled.

To the attainment of these ends and the accomplishment of other new and useful objects, hereinafter appearing, my invention consists in the features of novelty disclosed in the construction, combination and arrangement of parts and herein described and claimed, and shown in the accompanying drawings, which illustrate one embodiment of my invention, and in which—

Figure 1 is a central, longitudinal, vertical section of a magneto generator embodying my invention. Fig. 2 is a transverse vertical section on the line 2—2 of Fig. 1. Fig. 3 is a transverse, vertical section on the line 3—3 of Fig. 1, the end of the armature being shown in elevation. Fig. 4 is a horizontal section partly in elevation on the line 4—4 of Fig. 3. Fig. 5 is a detail perspective view of a device for holding the

clamping bolts from turning, and Figs. 6 to 13 inclusive are detail views of modifications of my improved pole-piece, Fig. 7 being a sectional view on line 7—7 of Fig. 6, Fig. 9 is a sectional view on line 9—9 of Fig. 8, Fig. 11 is a sectional view on line 11—11 of Fig. 10, and Fig. 13 is an end view of the pole-piece shown in Fig. 12. 60

In the drawings I have illustrated my invention as embodied in a magneto generator designed to be used more particularly for igniting the charge in gas engines of the single cylinder type adapted for rotation in either 65 direction, but it will be clearly manifest to one skilled in the art, after having obtained an understanding of my invention from the disclosures herein made, that my invention is not restricted to the particular structure 70 shown, nor is its application limited to single cylinder engines.

The magneto shown in the drawings has a casing or frame A which is preferably constructed as an inclosure so as to protect 75 the operating parts of the magneto from dirt and injury. Access, however, must be gained to the interior thereof at times for the purpose of inspection, cleaning and repair, hence it is necessary to occasionally 80 disassemble the structure. It is desirable, therefore, that the structure be capable of being assembled in operative relation without further adjustment than the mere placing together of the parts. 85

In the structure shown the frame A has journal bearings 1 and 2 at the ends thereof, preferably formed integral therewith. The frame is preferably divided into two sections separably fitted together at their abutting edges 3 and 4 respectively as shown in Figs. 1 and 2. These abutting edges are formed as lap or shoulder joints and are curved on arcs, the center of which is the axis of the journal bearings, hence when 95 the two frame sections are placed together the bearings will always properly line up without further adjustment. The sides 5 of the frame are faced off so that they lie in planes parallel to each other. The base 100 portion 6 of the frame projects laterally as shown, so as to form ledges 7 upon which the ends of the permanent field magnets 8 rest, hence the mag-

nets 8 will always be positioned properly in relation to the frame without the necessity of further adjustment each time the parts are assembled.

Each side of the frame is provided with a detachable field pole-piece which projects into the open side thereof and embraces the rotary armature D. In the structure shown in Figs. 1 to 4 inclusive, the pole-pieces are composed of arc-shaped plates 9 and flat supporting plates 10, but as shown in Figs. 6 to 9 inclusive and 12 and 13, they may be formed up from one piece of metal. The pole-piece plates 9 are preferably rectangular and are blanked out and formed or pressed up from sheet metal of suitable thickness. The pole-piece plates 9 after being given an arc-shaped formation are faced off flat as indicated at 12, (Figs. 2 and 3) so that they may be firmly mounted on the backing or supporting plates 19. The two plates comprising each pole piece may be securely fastened together by means of several rivets 13, the heads of which preferably do not project beyond the plate surfaces. The supporting plates are rectangular but somewhat longer than the field plates, and are provided with holes 10¹ at their corners through which bolts 14 may be inserted and screwed into the frame section (Fig. 4) to clamp the pole-pieces in position at the sides of the frame and at the same time hold the frame sections together. As is manifest, the pole-pieces also serve to completely close the open sides of the frame and prevent moisture and dirt from gaining access to the interior mechanism. The permanent field magnets 8 bridge the frame structure, and their lower end 8¹ as before mentioned rest on the ledges 7 of the base 6. These magnets may be firmly clamped flatly against the plates 10 by means of the plates or strips 15, the bolts 16 and nuts 17. The clamping bolts 16 may be inserted through suitable holes in the backing plates 10 from the inner sides thereof, and may be long enough to project beyond the magnets and receive the clamping plates or strips 15 and nuts 17. These bolts may be prevented from turning by means of small metal clips 18 (Fig. 5). The clips 18 as shown are placed between pole-piece plates 9 and 10 and one of their edges 19 are arranged to fit the slots in the heads 20 of the bolts. The edges 19 have lugs 21 to prevent the clips from becoming displaced endwise.

The armature D is preferably of the bipolar type comprising the two heads or poles 25 connected by a core 26, and a suitable winding 27 on the core between the poles. The ends of the armature may be provided with disks or circular plates 29 and 30 which may be secured thereto, so as to be easily disassembled, by means of a number 65 of screws 31. These end plates or disks 29

and 30 carry the centrally positioned stud shafts 32 and 33, arranged in axial alignment and rotatably mounted in the journal bearings 1 and 2 respectively. The shaft 33 is hollow and carries an insulating sleeve 34, 70 having a metal plug 35 inserted in its inner end. On this plug is a terminal clip 36, to which one end of the armature winding may be connected. A brush 37 is mounted in the outer end of the insulating sleeve 34 and operates in the hollow end of a binding post or terminal 38, and this brush is yieldingly seated in position during the rotation of the armature by means of a spring 39 interposed between the inner end of the brush 80 and plug. The binding post 38 is mounted in an insulating plug or cap 40 set into the end of the journal bearing 2 and is fastened in place by a set screw 41, whereby it may be readily removed and access gained to the interior of the bearing whenever desired. The other terminal (not shown) of the armature winding may be grounded directly on the armature metal as usual. The other shaft 32 projects beyond the end of the journal 90 bearing 1 a sufficient distance to receive a gear for driving the magneto.

Magneto generators of the character herein described are more particularly used in connection with the ignition systems of gas engines, and, as is well known, it is customary to mount the magneto on the frame of the engine in such position that a train of gears or a chain belt may be connected between the armature shaft 32 and the engine 95 shaft for the purpose of driving the magneto, and these driving mechanisms are proportioned to drive the magneto at a speed consistent with the speed of the engine, to secure the best sparking results. It is also customary to connect the insulated terminal 38 of the magneto with the corresponding insulated terminal of the make-and-break 100 sparking apparatus of the gas engine, and to ground the other terminal of the armature 105 winding on the frame of the machine.

My improved magneto is designed more particularly for use in connection with gas engines intended to run in either direction, and since the magneto is connected therewith by a positive driving mechanism, as above mentioned, the magneto must necessarily run in either direction corresponding to the engine. It is a matter of common knowledge in magneto generators of the bipolar type, that the alternating current wave reaches its maximum value when the polarity of the armature is reversed at a certain point in its revolution, hence the current is of maximum value for sparking 115 or ignition purposes at this point. This point, however, as is well known, changes in accordance with the direction of rotation of the armature. For instance, in the structure shown, during the rotation of the arm- 120

ture in the direction of the arrow (Fig. 3) the current rises to its maximum value when the armature poles 25 reach substantially the position indicated by the dotted line X—X. 5 During the opposite direction of rotation the current rises to maximum value at about the time the armature arrives in the position indicated by the dotted line Y—Y. In order, therefore, to secure the best sparking results, the magneto should be timed so that the spark takes place when the armature is in either of these positions, depending on the direction of rotation. This is usually done by adjusting the gear on the armature 10 shaft until the position of the armature is timed or coincides with the make-and-break apparatus of the engine. Hence, whenever the direction of rotation of the engine is reversed, it is necessary to change the adjustment of the magneto with respect thereto. In the present magnetos on the market the magneto must be partially disassembled so that the armature can be seen while the adjustment is being made. I avoid all of these 15 objections, I predetermine the positions of the armature and provide timing mechanism accessible from the outside of the magneto frame whereby the armature may be temporarily held in either of its predetermined positions without disturbing or disassembling the parts in any manner. This mechanism is arranged to automatically release the instant the armature is rotated after adjustment. Referring more particularly to Figs. 20 3 and 4, it will be observed that in the end of the frame section which carries the journal bearing 1, there is provided two small headed pins or plugs 45, one on each side of the shaft 32, and preferably arranged in a horizontal plane. These are freely movable longitudinally in the frame. They project outwardly beyond the casing in such manner that they may be readily pressed inwardly by the fingers. The end plate or disk 29 of the armature may be provided with a small 25 dépression or socket 47, so disposed that when the socket is alined with one or the other of the stop pins 45, the armature will be in one or the other of its predetermined positions, indicated by the dotted lines X—X or Y—Y, depending upon the direction of rotation of the armature. The head 46 of a stop pin, when the pin is pressed inwardly, 30 enters the timing socket 47 and thereby the armature may be held against rotation as long as the pressure is maintained on the pin, but as soon as the pin is released the rotation of the armature automatically throws the pin outwardly in a non-holding position. It will thus be seen that when 35 it is desired to time the magneto with the engine it is simply necessary to loosen the gear on the armature shaft, press inwardly the pin corresponding to the desired direction of rotation of the armature, and turn

the armature until the pin engages the depression 47. Thus the armature may be held in its predetermined position while the sparking apparatus is timed therewith. The gear on the armature shaft may then be 40 tightened. 70

In Figs. 6 to 13 I have shown several pole pieces of modified form, but all embodying my invention and constructed in accordance therewith. Figs. 8 and 9 disclose a punched or pressed metal pole piece constructed of two pieces of sheet metal, but the pole plate 9 thereof, instead of being faced off flat at its center and riveted to the center of the backing plate 10, is formed in the manner 45 shown in section in Fig. 9. The pole plate 9 has angularly disposed flanges 9¹ and these flanges have short lugs 10² on their edges, which are inserted through holes or notches in the backing plate and riveted. Figs. 6 50 and 7 and 10 to 13 inclusive illustrate pole pieces wherein the pole plate and the supporting or backing plate are combined into one piece of metal. In the form of pole piece (Figs. 6 and 7) the curved portion 9 of 55 the pole piece is obtained by punching and forming up the central portion of the sheet of metal, a portion of the metal 11¹ being left uncut to hold the curved and flat portions together. Figs. 10 and 11 show another one-piece pole piece by which the magnetic lines of force may be concentrated more 60 particularly in the edges of the plate. In this structure it will be seen that the plate is blanked out from a flat sheet of metal and 65 its upper and lower edges 11² bent or formed inwardly to angular positions in such manner that the edges 11³ lie in proper inductive relation to the armature, as indicated by the dotted lines 11⁴. Figs. 12 and 13 show a 70 simpler form of pole piece wherein the plate is curved to conform to the curvature of the armature, and is provided with short integral lugs or extensions 11⁵, having bolt holes 11⁶, whereby the pole piece may be attached 75 to the frame of the machine. 105

It will thus be observed that my invention is capable of various modifications without departing from the spirit thereof, and I wish it to be clearly understood that I am not 80 limited to the particular structures shown in the drawings. 110

What I claim as new is:

1. In a magneto generator of the class described, the combination of a frame divided 115 into a plurality of sections separably fitted together, and a pole-piece detachably secured thereto and holding said frame sections in assembled relation. 120
2. In a magneto generator of the class described, the combination of a frame divided 125 into a plurality of sections separably fitted together and having alined journal bearings, pole-pieces mounted on said frame and holding said sections in assembled relation. 130

3. In a magneto generator of the class described, the combination of a frame divided into a plurality of sections separably fitted together and having alined journal bearings, pole-pieces mounted on said frame and holding said sections in assembled relation, and a permanent magnet detachably clamped against said pole pieces.

4. In a magneto generator of the class described, the combination of an open-sided frame divided into two separable interfitting sections, pole-pieces disposed at the sides of said frame, and means securing said frame sections and pole-pieces in assembled relation.

5. In a magneto generator of the class described, the combination of a plurality of sections forming when assembled together a frame structure, alined journal bearings in said sections, and pole-pieces removably fastened to said sections, and adapted to maintain said sections in assembled relation.

6. In a magneto generator of the class described, the combination of a plurality of sections forming when assembled together a frame structure, alined journal bearings in said sections, pole-pieces removably fastened to said sections and adapted to maintain said sections in assembled relation, and an armature rotatably mounted in said bearings and freely removable therefrom when said framed sections are separated.

7. In a magneto generator of the class described, the combination of a plurality of sections forming when assembled an open-sided frame structure, pole-pieces closing the open sides of said frame, and means holding said frame-sections and pole pieces in assembled relation.

8. In a magneto generator of the class described, the combination of two bearing members adapted to aline when assembled, an armature rotatably mounted therein, and freely removable therefrom by disassembling said members, pole-pieces mounted on and removably holding said members in assembled relation, and a permanent field magnet fastened in engagement with said pole-pieces.

9. In a magneto generator, of the class described, the combination of a frame divided intermediate its ends into separable sections, pole-pieces spanning said sections, means securing said sections and pole-pieces in an assembled structure, bearings in said sections, an armature rotatable therein, and permanent field magnets positioned in contact with said pole-pieces.

10. In a magneto generator of the class described, the combination of a frame divided intermediate its ends into separable sections, pole-pieces spanning said sections, means securing said sections and pole-pieces in an assembled structure, bearings in said

sections, an armature rotatable therein and permanent field magnets positioned in contact with said pole-pieces, and means detachably holding said magnets in position.

11. In a magneto generator of the class described, the combination of an open-sided frame divided vertically into two sections, pole-pieces secured to and holding said sections together and extending into the open sides of said frame, an armature rotatably mounted in said frame and positioned between said pole-pieces, and permanent magnets rising alongside of and clamped against said pole-pieces.

12. In a magneto generator of the class described, the combination of a sectional frame and pole-pieces assembled together, permanent field magnets clamped against said pole-pieces, and ledges on said frame for positioning said magnets.

13. In a magneto generator of the class described, the combination of a frame having alined journal bearings, an armature rotatably mounted in said bearings, a pole-piece mounted on each side of said frame and projecting into said frame in position to embrace said armature, and a permanent field magnet bridging said frame and having its end portions detachably clamped against said pole-pieces.

14. In a magneto generator of the class described, the combination of a frame having journal bearings and divided vertically on an arc concentric with said bearings, an armature rotatable in said bearings and removable therefrom by the separation of the parts of the frame, pole-pieces common to and holding said frame parts in assembled relation, and field magnets arranged in position against said pole-pieces.

15. In a magneto generator of the class described, the combination of a frame having journal bearings and divided vertically on an arc concentric with said bearings, an armature rotatable in said bearings and removable therefrom by the separation of the parts of the frame, pole-pieces common to and holding said frame parts in assembled relation, a base for said frame forming ledges at the sides thereof, permanent field magnets having their ends resting on and positioned by said ledges, and means detachably clamping said magnets against said pole-pieces.

16. In a magneto generator of the class described, the combination of frame having bearings in the end thereof and centrally divided into two parts on a curve concentric with the axis of said bearings, an armature rotatable in said bearings and freely removable therefrom when the frame parts are disassembled, members bridging the corresponding sides of said frame parts and holding said parts in assembled relation,

- 5 pole members carried by said members and embracing said armature, and permanent field magnets having their poles clamped in contact with said bridging members.
- 10 6 24. In a magneto generator of the class described, the combination of a frame divided into separable sections, bearings in the 60 said frame adapted to aline when said sections are assembled, a sheet metal plate disposed on each side of said frame and holding said frame sections in assembled relation, a curved pole plate carried by said 65 sheet metal plate and projecting into said frame, an armature rotatable in said bearings between said pole plates and freely removable therefrom when the sections thereof are disassembled, field magnets removable 70 mounted in engagement with said sheet metal plates, stop pins mounted in the end of said frame and accessible from the exterior thereof and adapted to engage and temporarily hold said armature in a predetermined position corresponding to the period in its rotation wherein the maximum current is developed, said pins being adapted to be manually operated for holding the armature and to be automatically rendered 80 inoperative when the armature is permitted to rotate.
- 15 75 25. The improved magneto generator for ignition purposes herein described, comprising in combination a frame divided into 85 separable sections and having bearings in the ends thereof adapted to aline when the sections are assembled, an armature rotatably mounted in said bearings and freely removable therefrom when the frame sections are disassembled, sheet metal pole pieces 90 detachably mounted at the sides of said frame and holding said sections in assembled relation and disposed in inductive relation to said armature, stop devices 95 mounted in the end of said frame, operable from the exterior of the frame and arranged in predetermined positions corresponding to the positions in the rotation of said armature wherein the maximum current is delivered, said armature having recesses at its end adapted to be engaged by whichever stop device is actuated to temporarily hold the armature in the particular predetermined position corresponding to the 100 direction of rotation of the armature.
- 20 105 26. A pole-piece for magneto generators comprising a plate of sheet metal formed to the proper curvature, and a backing plate fastened thereto.
- 21 45 27. A pole-piece for magneto generators comprising a flat plate of sheet metal, and a curved sheet metal plate fastened thereto.
- 28 50 28. A pole-piece for magneto generators composed of two rectangular sheet metal plates riveted together, one of said plates being curved to conform to the curvature of the armature with which it is to be used.
- 29 55 29. A pole-piece for magneto generators composed of two rectangular sheet metal plates riveted together, one of said plates being shorter than the other plate and curved to conform to the curvature of the armature with which it is to be used.
- 30 35 30. 19. A pole-piece for magneto generators comprising an arcuate sheet metal pole-piece member having a flat sheet metal supporting member substantially tangential to the center of said pole-piece member.
- 31 40 31. 20. A pole-piece for magneto generators comprising a plate of sheet metal formed to the proper curvature, and a backing plate fastened thereto.
- 32 45 32. 21. A pole-piece for magneto generators comprising a flat plate of sheet metal, and a curved sheet metal plate fastened thereto.
- 33 50 33. 22. A pole-piece for magneto generators composed of two rectangular sheet metal plates riveted together, one of said plates being curved to conform to the curvature of the armature with which it is to be used.
- 34 55 34. 23. A pole-piece for magneto generators composed of two rectangular sheet metal plates riveted together, one of said plates being shorter than the other plate and curved to conform to the curvature of the armature with which it is to be used.
